FISHING REEL

Robert Mimeur, Cluses, France, assignor to Carpano &
Pons, Cluses, France, a French company

Filed Mar. 3, 1966, Ser. No. 1,281

Claims priority, application France Sept. 4, 1965

Term of patent 14 years

(Cl. D22—25)

FIG.1

FIG.2

Des. 208,910

PAGE 2

FIG.3

FIG.4

FIG.5

FIG.6

FIGURE 1 is a side elevational view of the fishing reel, taken from one side thereof;

FIGURE 2 is a top view thereof;

FIGURE 3 is a side elevational view thereof;

FIGURE 4 is a bottom view thereof;

FIGURE 5 is a front elevational view;

FIGURE 6 is a rear elevational view thereof.

The characteristic feature shown in my design resides in the specific configuration of the main gear housing, as shown.

I claim:

The ornamental design for a fishing reel, as shown and described.
